Primary Examiner—A. Hugo Word

[57] CLAIM

The ornamental design for a sawbuck, substantially as shown and described.

DESCRIPTION

FIG. 1 is a perspective view of a sawbuck showing my new design including a log in phantom lines.

FIG. 2 is a perspective view of the opposite end, omitting the log.

FIG. 3 is a different perspective view of the end shown in FIG. 1, including the log in phantom lines.

The log in phantom lines has been shown for illustrative purposes only.
